UNITED STATES PATENT OFFICE

JESSE L. LAMONT, OF GENESEO, ILLINOIS

SIGNAL DEVICE

Application filed November 15, 1929. Serial No. 407,460.

This invention relates to automatically operated signals for railway crossings described and claimed in my copending application Serial Number 256,428, filed Feb. 23, 1928, of 5 which the present case is a continuation in part.

An object of the invention is the provision of a signal for railway crossings in which a signal having warning indicia is moved to a 10 visible position by means of a motor and related mechanism, the motor in turn being controlled by an electric circuit closed or opened by a plurality of switches, the switches being actuated by relays in a closed circuit connected with the track.

A further object of the invention is the provision of a signal for railway crossings in which the operating mechanism of a movable signal actuates switches for controlling circuits that include a motor for moving the signal by means of instrumentalities to an operative or an inoperative position, a closed circuit being employed for controlling a relay for maintaining the circuit to the motor open 25 while being shorted when the train moves into a block adjacent the railroad crossing.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure 30 from the salient features of the invention as expressed in the appended claims.

In the drawings:

Figure 1 is a view in elevation of the railway crossing signal constructed in accordance with the principles of my invention.

Figure 2 is a view in perspective of a weighted arm.

Figure 3 is a vertical section taken along 45 the line 3—3 of Figure 1.

Figure 4 is a fragmentary vertical section through the operating mechanism for the weighted arm and signal.

Figure 5 is a view in perspective of a switch 50 arm connected with the circuits.

Figure 6 is a vertical section taken along the line 6—6 of Figure 3.

Figure 7 is a horizontal section taken along the line 7—7 of Figure 1.

Figure 8 shows more or less diagrammatically one form of electrical circuit for controlling the signal.

Figure 9 is a modified form of the electric circuit as applied to a single track.

Referring more particularly to the drawings, 10 designates generally a frame having an opening 11 at its upper end through which a signal 12 is adapted to be displayed. Below this opening, the frame work is covered by means of a front face 13 and a rear face 14 when the said signal is disposed in an inoperative position. The lower portion of the frame work is provided with a housing 15 in which is mounted the operating mechanism for the signal to be presently explained.

The signal is provided with rollers 16 rotatably mounted at 17 at the side edges of the signal 12 and adapted to be received within guides 18 secured to the side edges 75 of the frame 10.

In the casing 20 is mounted a worm gear 22 which is secured to a shaft 23 having its opposite end projecting beyond the side walls of the casing. A worm 24 meshes with the worm gear 22 and is secured to a shaft 25 rotatably mounted in bearings 26 formed in the casing 20.

The weighted arm 30 is secured at 31 to the inner end of the shaft 23 and is provided with a weight 32 at one end. The opposite or lower end is pivotally connected at 33 to a rod 34 which extends upwardly and is connected at 35 to the upper end of the signal 12.

A rotatable member 40 is secured to the shaft 23 at its outer end and is provided with cam portions 41 and 42 adapted to operate a switch arm 61. The rotatable member has a portion 43 for a purpose which will be presently explained.

A bracket 45 is secured to the shelf 21 and the switch arm 61 which is formed of resilient material is secured to a block 46 extending laterally from the bracket 45.

Referring more particularly to Figure 9 it will be seen that a battery 80 is connected by a wire 81 to one rail 82 of a single track while a wire 83 connects the other pole of the battery to a rail 84 of said track. It will be noted that the rails 85 and 86 are insulated from the rails 82 and 84 as shown at 84^a. A wire 87 connects one terminal of a solenoid or relay 88 with the rail 82 while a wire 89 connects the other terminal of the solenoid with the rail 84. An armature 90 is actuated by the solenoid 88 normally to move an arm 91 of a switching element in engagement with a contact 92 which in turn is connected by a wire 69 with a contact member 64.

A wire 95 connects one pole of a battery 96 with the arm 91 while a wire 97 connects the other pole of the battery to a motor 98. Wires 99 and 100 connect a lamp 101 with the wire 97 and with a wire 67. A resistance 103 is in series with the wires 100 and 67. A spring 106 is adapted to move arm 91 into engagement with contact 104 when the arm 25 is released by the solenoid 88.

The wire 69 connects the contact member 92 with the contact 64. The movable arm 61 is adapted to move its contact member 62 alternately in engagement with a contact 63 or the contact 64. A wire 65 connects the movable arm 61 of the double throw switch with the motor 98.

The operation of the device illustrated in Figs. 1 to 7, inclusive, and Figure 9 is as follows: The parts shown in these figures are in a position where the signal 12 is inoperatively disposed and invisible to the travelling public.

When the train moves into the insulated section of the track represented by the rails 82 and 84, the battery 80 is short circuited and the electro-magnet 88 is de-energized permitting the spring 106 to move the switch member 91 into engagement with the contact 104, thereby closing the circuit through wire 67, contact 63, switch element 61, wire 65, motor 98 and through the battery 96 and wire 95 back to the movable switch element 91. At this time the circuit to the lamp 101 is likewise closed which will illuminate the signal 12. Since the motor 98 has been set into operation it will revolve the shaft 25 in a direction which will cause the weighted arm 30 to be moved to a position opposite to that shown in Figure 1, thereby placing the signal 12 in visible position. While the signal is being moved to its uppermost and operative position, the free end of the suitable element 61 is riding over the portion 40 of the cam so that contact 62^a is in engagement with contact 63. When the cam has passed through 180°, the arm 61 will engage the portion 43^a and break the circuit to the motor since the contact 62^a is moved out of engagement with the contact 63 while

contact 62 is moved into engagement with contact 64. The circuit connected with the contact 64 is broken and the motor remains inoperative. This is due to the fact that the member 91 is in engagement with the contact 104.

When the train passes beyond the insulated rails 82 and 84, the current from the battery 80 will pass through the rails, through wires 87 and 89 and the magnet 88, thereby causing the armature 90 to move the switch element 91 away from the contact 104 and into engagement with the contact 92 against the tension of the spring 106. Since the movable switch contact 62 engages the contact 64, current from the battery 96 will pass through the motor 98, through the switch represented by the elements 61, and 64, wire 69, the switch represented by the elements 91, 92 and wire 95. It will be appreciated that at this time the circuit to the lamp 101 is broken. The motor 92 actuates the cam 40 and shafts 23 and 25 and the signal is lowered to an invisible position. As soon as the free end of the member 61 slips off the portion 43^a, the circuit to the motor is broken by reason of the fact that the contact 62 is moved away from the contact 64 and the switch arm 91 is in the position shown in Figure 9.

The weight 32 carried by the arm 30 balances or equalizes the weight of the signal 12 so that the signal will be retained in its operative upper position when the arm is located at dead center.

Referring more particularly to the form shown diagrammatically in Fig. 8 it will be seen that pairs of rails 82, 84, and 82^a, 84^a disclose a double track system in which the trains are adapted to travel in opposite directions. The battery 80 is in circuit with the rails 82 and 84 by means of wires 81 and 83. Wires 120 and 121 complete the circuit of said battery to a magnet 122 having a movable armature 123 controlling the switch element 124 which is adapted to engage contacts 125, 126. A wire 127 connects the contact 125 to one pole of a battery 128 while a wire 129 connects contact 126 with a contact 130. A wire 131 connects the other pole of the battery 128 with one terminal of the electromagnet 88. A wire 133 connects the other terminal of the magnet with a contact 134.

A magnet 137 energized by a battery 80^a through wires 135, 136 and rails 82^a and 84^a controls the position of the armature 140 normally retaining the switch element 139 in engagement with contacts 130 and 134 so that the circuit to the magnet 88 will remain closed.

The operation of the device shown in Figure 8 is as follows: When the train moves on the rails 82 and 84, the battery 80 is short circuited, thereby de-energizing the magnet 122 so that the switch element 124 is moved out of engagement with the contacts 125 and

126 breaking the circuit to the battery 128 and to wire 129, switch element 139, wire 131 and the solenoid 88. At this time the armature 90 releases the switch element 91 to the action of the spring 106 so that the contact 92^a will engage the contact 92 and close the circuit to the battery 96, the motor 98 and the lamp 101 through wire 67, switch element 61, contacts 62^a and 62, and wires 65, 97 and 99^a. The motor revolves the cam 40 and shafts 23 and 25 which cause the signal 12 to be moved to its exposed position. At the time that the signal reaches the end of its exposed position, the free end of the member 61 will be moved on the portion 43^a of the cam 40 so that the contact 62 will engage the contact 64 and thereby break the circuit to the motor and retain the signal in its exposed position until the train moves out of the block.

20 As soon as the train moves beyond the insulated rails 82 and 84 the current from the battery 80 will energize the solenoid 122, closing the switch member 124 and thereby closing the circuit to the solenoid 88 causing the armature 90 to move the member 91 so that it will engage the contact 104 and close the circuit to the motor. Since the contact 62 of the switch member 61 is in engagement with the contact 64 the current from the battery 96 will pass through the switch member 91, wires 69 and 65, motor 98 and wire 97. At this time the free end of the switch member 61 is riding on the portion 43^a of the cam 40 which is being revolved by the shafts 23 and 25 while at the same time the crank arm 30 through the rod 34 is lowering the signal 12 to its inoperative position in the housing 13. At the time the signal 12 reaches its lowermost position, the free end of the member 61 will have reached the portion 43, thereby moving the contact 62 out of engagement with the contact 64 and breaking the circuit to the motor. The contact 62^a is now in engagement with the contact 63.

45 I claim:

1. A signalling system for railway crossings comprising a movable signal, a casing for normally housing the signal, a motor, a signal actuating means actuated by the motor, a plurality of open electrical circuits associated with the motor, a double acting switch operated by the motor adapted to alternately aid in closing one circuit while opening another circuit, a second switch, electro-magnetic means for actuating the switch and cooperating with the first switch for closing one of the circuits and opening the other circuit, a closed circuit connected with the rails of a railway crossing adapted to be short circuited by a moving train for controlling the magnetic means, and a lamp connected with the open circuits and adapted to be illuminated when the circuits are closed by the co-operating switches.

65 2. A signalling system for railway cross-

ings comprising a movable signal, a casing normally housing the signal, an electrical motor, means for periodically causing actuation of the motor when a train moves into and out of a block adjacent the railway crossing, a shaft driven by the motor, a crank arm having a weight at one end connected intermediate its ends to the shaft, a rod pivotally connected at one end to the end of the crank arm which is opposite to the end having the weight, the other end of the rod being connected with the signal.
